JAMES A. FERGUSON, OF PLUMMER, IDAHO.

KEYLESS PADLOCK.

1,234,454.

Specification of Letters Patent. Patented July 24, 1917.

Application filed September 11, 1916. Serial No. 119,558.

To all whom it may concern:

Be it known that I, JAMES A. FERGUSON, a citizen of the United States, residing at Plummer, in the county of Benewah and 5 State of Idaho, have invented certain new and useful Improvements in Keyless Padlocks, of which the following is a specification.

This invention relates to the class of key- 10 less padlocks and more particularly to a combination lock having a locking mechanism mounted within a cylindrical barrel whereby the keeper will be locked in position and which can only be released by one 15 who has knowledge of the combination.

A further object of this invention is the provision of a keyless padlock which consists of comparatively few parts and is simple in construction, but durable and well 20 adapted to withstand the rough usage to which devices of this character are ordinarily subjected.

For a full description of the invention and the advantages and merits thereof, reference 25 is to be had to the following description and the accompanying drawings, wherein is illustrated the preferred form of my invention, in which,

Figure 1 is a side elevation.

30 Fig. 2 is a vertical transverse section.

Fig. 3 is a horizontal section on the line 3-3 of Fig. 2.

Fig. 4 is a horizontal section on the line 4-4 of Fig. 2.

35 Fig. 5 is a plan view of the lock showing the different positions of the keeper in dotted lines.

Referring to the drawing, wherein is 40 illustrated the preferred form of my invention, and in which like numerals of reference indicate corresponding parts throughout the several views, the body portion of the lock comprises a cylindrical barrel 1 closed at its bottom with a wall 2 and open 45 at its top end. The open end of the barrel is provided with a closure plate 3 having the depending annular flange 4 fitting into an annular groove 5 formed at the upper edge of the barrel 1. Integrally formed with the 50 edge of the closure plate 3 is an annular vertical flange 6 provided with a cut-out portion 7 the purpose of which will be presently described.

Mounted within the barrel 1 and resting 55 on the bottom wall 2 is a bearing plate 8 having a central opening 9 adapted to re-

ceive the cylindrical locking bolt 10 at its lower end. The closure plate 3 is also provided with a central circular opening through which the upper end of the locking 60 bolt 10 is extended and the extreme upper end of the locking bolt carries an arcuate keeper member 11 having the downwardly extending obliquely disposed keeper arms 12. The terminals of the keeper arms 12 are 65 in sliding contact with the upper surface of the closure plate 3 thus permitting the locking bolt 10 to be rotated while the ends of the arms 12 slidably contact with the upper surface of the closure plate. 70

Two locking disks 13 and 14 are fixed within the barrel 1 and disposed in superposed relation and have central apertures for receiving the locking bolt 10. The disk 13 is disposed above and in spaced relation 75 to the bearing plate 8 and is provided with three radially extending slots 15 equally spaced apart and communicating with the central opening in the said disk. Extending radially from the locking bolt 10 is a plurality of locking pins 16, three in number, and are spaced from the lower end of the locking bolt at a distance slightly greater than the thickness of the bearing plate 8 whereby the pins will be normally above the plate 8 when 80 the locking bolt is in locked position. The disk 14 is also provided with three radially extending slots 17 communicating with the central opening in the disk and these slots 17 are arranged so as to be out of vertical alignment with the slots 15 in the lower disk 13 85 as clearly shown by Fig. 4 of the drawing.

In operating the lock, the person who has knowledge of the combination, will rotate the keeper 11 thereby also rotating the locking bolt 10 until the locking pins 16 are disposed in alignment with the slots 15 in the disk 13. The person operating the lock will, of course, have to have knowledge of the combination, and this knowledge will include the position which the keeper should assume when the pins 16 are aligned with the slots in the disks. The locking bolt may then be raised, the locking pins 16 passing through the slots 15 and a further rotation 95 of the locking bolt, to the proper point, will cause the pins 16 to be moved into vertical alignment with the slots 17 in the disk 14. The locking bolt may then be further raised 100 of the locking bolt, to the proper point, will cause the pins 16 to be moved into vertical alignment with the slots 17 in the disk 14. The locking bolt may then be further raised 105 to a height sufficient to permit the keeper arms 12 to be withdrawn from the hasp or staple to which it has been attached. The 110

cut-out portion 7 permits the arms to be easily withdrawn from the hasp or staple to which they are attached when the lock is in applied position. It will be noted that 5 the position of the slots in the disks through which the pins pass when the locking bolt is being extracted, provide a staggered passage for the pins that will be baffling to a person attempting to open the lock without 10 knowing the combination.

Fig. 5 illustrates the different positions which the keeper assumes when the lock is being operated. In the first place, when the lock is in locked position, the keeper will be 15 in the position shown by full lines with one of the arms of the keeper alined with the center of the depression 7. When the front arm of the keeper is moved around to the right to the position shown by dotted lines marked "first position," the pin 16 will be 20 alined with the slots 15. When the bolt is then lifted, and the arm turned to the opposite direction to the position indicated by dotted lines marked "second position," the 25 pin 16 will be alined with the slots 17 and the bolt may then be again raised.

From the foregoing it will be observed that a very simple and durable keyless padlock has been provided, the details of which 30 embody the preferred form. I desire it to be understood, however, that slight changes in the minor details of construction may be made without departing from the spirit of the invention or the scope of the claims here- 35 unto appended.

I claim:

1. A lock comprising a barrel having a closure plate mounted on its open end, a cylindrical rotatable locking bolt disposed 40 centrally in the barrel, a bearing plate mounted in the bottom of the barrel for receiving one end of the said rotatable bolt, a plurality of locking pins carried by the said locking bolt, and means arranged within the 45 barrel for providing a staggered passage through which the said locking pins must pass when the said bolt is extracted.

2. A lock comprising a barrel of cylindrical formation having a closure plate 50 mounted on one end and provided with a central circular opening, a cylindrical locking bolt disposed centrally within the barrel, a keeper of arcuate formation having obliquely disposed arms the terminals of 55 which contact with the surface of the said closure plate, and means forming a staggered passage for preventing the extraction of the locking bolt from the barrel.

3. A lock comprising a barrel of cylindrical formation having a closure plate 60 mounted on one end and provided with a central circular opening, a cylindrical locking bolt disposed centrally within the barrel, a keeper of arcuate formation carried by the said locking bolt and having obliquely disposed arms the terminals of 65 which contact with the surface of the said closure plate, a plurality of locking pins carried by the said locking bolt, and means arranged within the barrel for preventing the extraction of the locking bolt and providing a staggered passage for the said locking pins.

4. A lock comprising a barrel of cylindrical formation having a closure plate 70 mounted on one end and provided with a central circular opening, a cylindrical locking bolt disposed centrally within the barrel, a keeper of arcuate formation carried by the 75 said locking bolt and having obliquely disposed arms the terminals of which contact with the surface of the said closure plate, a plurality of locking pins carried by the said locking bolt, a plurality of disks mounted within the barrel and provided with radially extending slots adapted to permit the 80 passage of the said locking pins centrally through the barrel.

5. A lock comprising a barrel of cylindrical formation having a closure plate 85 mounted on one end and provided with a central circular opening, a cylindrical locking bolt disposed centrally within the barrel, a keeper of arcuate formation carried by the 90 said locking bolt and having obliquely disposed arms the terminals of which contact with the surface of the said closure plate, a plurality of locking pins carried by the said locking bolt, a plurality of disks mounted within the barrel and provided with radially extending slots adapted to 95 permit the passage of the said locking pins centrally through the barrel, the said disks being arranged in superposed relation to each other and each disk having radially 100 extending slots in the same spaced relation to each other as the said locking pins, the slots in one disk being out of alinement with the slots in the adjacent disk.

In testimony whereof I affix my signature 110 in presence of two witnesses.

JAMES A. FERGUSON.
